UNITED STATES PATENT OFFICE.

WILMOT B. THURLOW, OF GREEN'S LANDING, MAINE.

DESIGN FOR A WEAR-PLATE FOR BASKETS.

SPECIFICATION forming part of Design No. 25,994, dated September 8, 1896.

Application filed July 14, 1896. Serial No. 599,192. Term of patent 7 years.

To all whom it may concern:

Be it known that I, WILMOT B. THURLOW, a citizen of the United States, residing at Green's Landing, in the county of Hancock 5 and State of Maine, have invented and produced a certain new and original Design for Wear-Plates for Baskets, Boxes, and Similar Articles; and I do declare the following to be a full, clear, and exact description of the invention, such as will enable others skilled in the art to which it appertains to make and use the same.

My invention relates to wear-plates for baskets, boxes, and similar articles.

15 Figure 1 is a perspective view of a wear-plate embodying my design. Fig. 2 is a transverse section of the same on the broken

line 2 2 of Fig. 1, and Fig. 3 is a similar view on the line 3 3.

The leading feature of my design consists 20 of a plate having one side flat, the other rounded in form, and tapering from its center to its pointed ends.

What I claim is—

The design for a wear-plate for baskets, 25 boxes and the like, substantially as herein shown and described.

In testimony whereof I hereunto affix my signature in presence of two witnesses.

WILMOT B. THURLOW.
